Monte, Calif., a corporation of California

Filed Nov. 26, 1962, Ser. No. 72,600

Term of patent 14 years

(Cl. D91—1)

FIG. 1 is a perspective view showing the front and one side of a combined filter and stand showing our new design;

FIG. 2 is a top plan view thereof;

FIGURE 3 is a rear elevational view of the side opposite that shown in FIG. 1; and

FIG. 4 is a side elevational view thereof.

The fragmentary portions shown in broken lines are included for illustrative purposes only, and said portions are omitted in FIGS. 2 to 4 for the convenience of illustration.

We claim:

The ornamental design for a combined filter and stand or similar article, substantially as shown and described.
